United States Patent Office.

VIRGIL DRAPER, OF ATTLEBOROUGH, MASSACHUSETTS, ASSIGNOR TO OSCAR M. DRAPER, OF SAME PLACE.

Design No. 4,749, dated April 4, 1871.

DESIGN FOR A CHAIN-LINK.

The Schedule referred to in these Letters Patent and making part of the same.

To all whom it may concern:

Be it known that I, VIRGIL DRAPER, of Attleborough, in the county of Bristol and State of Massachusetts, have invented a new and improved Design for an Ornamental Chain-Link; and I do hereby declare that the following specification, taken in connection with the drawing, is a full, clear, and exact description thereof.

The link shown in the drawing is composed of three members, *a*, *b*, and *c*.

The first member, *a*, is a link proper, made of either flattened or round wire.

The second member, *b*, is a bar, whose length is as much less than the long diameter of the link as will

afford at each end openings *d*, for the insertion of rings, to connect together the several links which compose the chain.

The third member, *c*, is a fillet, which embraces the two other members, and which may be either plain or ornamented.

What I claim as my invention, and desire to secure by Letters Patent, is—

The new design for an ornamental chain-link, substantially as herein described.

VIRGIL DRAPER.
